LOOM STOP MOTION

Jacob Neubauer, Manchester, Conn.

Application July 13, 1944, Serial No. 544,661

4 Claims. (Cl. 139—337)

This invention relates to looms and particularly to a stop motion therefor to promptly stop operation of the loom if any one of the harness frames fails to properly function.

More particularly the invention relates to a harness stop motion for looms in which the harness frames are operated in pairs, that is, pairs of adjacent harness frames are moved simultaneously either both up or both down.

An object of the invention is to stop the loom promptly when one of a pair of harness frames, which are designed to operate simultaneously, fails to move with its mate.

A feature that enables the above object to be accomplished is that the adjacent harness frames operating together in pairs are provided with a loop of flexible cord attached preferably by screw eyes or other means at one of the ends of each of the frames, the series of loops also being attached to a stop motion device of any type applied to the main driving shaft of the loom.

Another feature that is important is that the loop connecting the ends of a pair of harness frames operating together is sufficient in length to permit simultaneous operation of the harness frames from one position to the other without actuating the stop motion but when one of a pair of harness frames moves without its mate the loop is drawn in a direction so that a pull is effected on the stop motion latch or other mechanism released by the pull of the cord so that the loom will be instantly stopped.

With the above and other objects in view, the invention includes the features of construction and operation set forth in the following specification and illustrated in the accompanying drawings.

In the accompanying drawing annexed hereto and forming a part of this specification, I have shown the invention schematically in a conventional form of broad loom but it will be understood that the invention can be otherwise embodied and that the drawing is not to be construed as defining or limiting the scope of the invention, the claims appended to this specification being relied upon for that purpose.

In the drawing:

Figure 1 is a front elevation of a conventional form of loom showing schematically a form of clutch for starting and stopping the loom.

Fig. 2 is a perspective view of a group of harness frames showing pairs of frames in their two operative positions with their stop motion actuating members, and

Fig. 3 is a similar view of a pair of harness

frames in which one of the pair has failed to operate with its mate and has actuated the stop motion.

In the above-mentioned drawing there has been shown but one embodiment of the invention which is now deemed preferable, but it is to be understood that changes and modifications may be made within the scope of the appended claims without departing from the spirit of the invention.

Briefly, and in its preferred aspect, the invention may include the following principal parts: First, a group of harness frames arranged in a loom adapted to be operated in pairs; second, a stop mechanism for the loom having some form of releasable latch for disengaging the driving connections for the loom; third, flexible connections from each pair of harness frames to an operating member for releasing the latch when 10 one of any pair of harness frames fails to move with its mate.

Referring more in detail to the figures of the drawing, there is shown the principal operative parts of a standard form of loom. The frame 10 supports a number of harness frames 11 actuated by any form of dobby or other pattern control motion (not shown). The frames are supported for up and down movement as called for by the 15 pattern being woven through straps 12 attached to operating bell cranks 13 controlled by the dobby or other pattern control motion.

In setting up a loom for a warp it is usually desirable in weaving many types of fabrics to operate the frames 11 in pairs of adjacent frames 20 as shown in Fig. 2 of the drawing. By this means the warp threads may be more evenly spread out through the harness and the action of the harness improved. Advantage of this arrangement in pairs of the frames 11 is availed of to operate a stop motion for the loom in the event any one of a pair of frames fails to operate with its mate. For this purpose attaching means 13 25 in the form of screw eyes are provided in one of the ends of each frame. A loop of flexible cord 14 passes through the eyes 13 of each of a pair of frames. The length of loops 14 is ample to permit movement up or down of the frames 11 forming a pair without tightening the loop or 30 forcing the end connection 15 to move a substantial distance toward the frames. This will be obvious by an inspection of Figs. 2 and 3.

Each of the loops 14 is attached to a cable 16 as shown in Fig. 2 so that when any one frame 35 of the entire group fails to operate one of the

loops 14 is drawn taut and pulls the cable 16 to the right as seen in the figures.

The opposite end of cable 16 is attached to a latch member 17 normally holding the clutch or starting lever 18 in position to hold the clutch 19 in driving position as shown in Fig. 1. When cable 16 is pulled toward the right, latch 17 is disengaged from lever 18 thus allowing spring 20 to disengage the driving clutch 19 and stop the loom.

The driving connections from pulley 21 to the driving shaft 22 are only diagrammatically shown and may be of any standard or usual form. Any form of disengaging means may be used in place of the latch 17 shown in the drawing. The purpose is to promptly disconnect the driving connections between the driving pulley as soon as a frame 11 fails to operate properly and stop rotation of shaft 22.

When a harness frame has failed to move with its mate and the cable 16 has pulled the latch 17 to its clutch releasing position, the latch cannot be returned to its engaging position until the harness frame failure has been corrected. Until that has been done the clutch 19 will be retained in its open position by the spring 20 and the loom cannot be operated.

It will be understood that this stop motion is supplemental to the usual manual stopping means (not shown) for the loom and of any other stop motions controlled by breakage of the warp or filling threads.

What I claim is:

1. A loom stop motion comprising in combination, a plurality of harness frames operable in pairs, driving means for said loom having a releasable connection, and flexible connections

from frames operating in pairs to said connection, whereby when the harness frames forming a pair separate the driving connection will be released.

5. 2. A loom stop motion comprising in combination, driving means for said loom having a releasing lever, a plurality of harness frames, means to operate said frames in pairs of adjacent frames to their upper and lower operative positions, connections extending from the frames constituting a pair to a stop motion lever, whereby movement of one of the frames of a pair without its mate will actuate said lever and stop said loom.

15. 3. A loom stop motion comprising in combination, driving means for said loom having a releasing lever, a plurality of harness frames, means to operate said frames in pairs of adjacent frames to their upper and lower operative positions, a loop of flexible material attached to adjacent 20 ends of frames constituting a pair, a flexible member connecting said loop to a stop motion actuating lever, whereby when the frames of a pair separate said loop is drawn in a direction to actuate said stop motion.

25. 4. A loom stop motion comprising in combination, a plurality of harness frames operable in pairs, driving means for said loom having a releasable connection, flexible connections from frames operating in pairs to said releasable connection, whereby when a harness frame of a pair fails to move with its mate said connection in said driving means will be released, said means preventing re-engagement of said driving connection until said harness frame failure has been corrected.

JACOB NEUBAUER.
